UNITED STATES PATENT OFFICE

JEREMIAH J. COLLINS, OF ORANGE, NEW JERSEY, ASSIGNOR TO RAYMOND CONCRETE
PILE COMPANY, OF NEW YORK, N. Y., A CORPORATION OF NEW JERSEY

METHOD OF PROTECTING PILES FROM EROSION

Application filed October 11, 1929. Serial No. 398,841.

This invention pertains to improvements in concrete piles for certain conditions of dock and pier work under which the piles must be protected from erosion.

As is well known, when piles are subjected to the rise and fall of tides, the portions of the piles exposed alternately to air and water are subject to rapid erosion. It has been customary to meet that condition by simply making the piles large enough in cross-section so they would be able to carry their loads even after considerable erosion has taken place. That, however, is not a satisfactory solution, especially when it calls for extra heavy piles, as for instance when piles 24 inches square and 70 to 80 feet long are called for. Such piles weigh 20 to 25 tons each. Special cranes are required for handling them, and special pile drivers for driving them. The transportation and rental charges on such machinery are so high as to be often prohibitive.

In order to successfully meet the conditions outlined above the present invention contemplates the placing of pipe piles, protected by external concrete sleeves extending upwardly from below the low water line to the top of the piles. A pipe pile is formed by first driving a steel pipe of sufficient strength and stiffness to resist crushing, and then filling the pipe with concrete. If the pile is long, the pipe is composed of lengths coupled together. The pipe can be transported while uncoupled, coupled on the job, and, on account of its comparatively light weight, can be driven by an ordinary pile driver.

Such a pile, in tide water, requires protection only on the surface which is alternately wet and dry. The area below the low water mark will in some waters last indefinitely. Even if the pipe should ultimately rust away, the inner concrete, being reinforced and thoroughly cured, will still function as a concrete pile.

The principal object of the invention is to provide protection for the alternately wet and dry portion.

Further and other objects and advantages 50 will be apparent from the specification and

claims, and from the accompanying drawings which show by way of illustration what is now considered the preferred embodiment of the invention.

Fig. 1 is a view, partly broken away, showing a completed pipe pile in position before the protecting shell is applied. 55

Fig. 2 is a view showing the first steps of the application of the concrete shell, the shell being in cross section. 60

Fig. 3 is the same view as Fig. 2, after the shell has been secured in position and the space between shell and pile filled with grout. 65

Fig. 4 is a side view of Fig. 3.

Fig. 5 is a view on the line 5-5 of Fig. 3. 65

Fig. 6 is a view on the line 6-6 of Fig. 3.

Fig. 7 is a view on the line 7-7 of Fig. 3.

Fig. 8 is a view of the completed pile in position with protecting shell grouted in place. 70

Referring to Fig. 1, 9 is the pile, in which 10 designates a steel pipe which has been provided with a driving shoe 12, then driven to substantial footing 14 and finally filled with concrete 16 in which have been embedded reinforcing bars 18. The above pile forms no part of the present invention. 75

After the pile has been placed, a reinforced concrete sleeve is applied, extending from below low water mark to the top of the pile. 80 The construction of the shell 20 will be understood from Figs. 2 and 6. It is simply an annular sleeve having an internal diameter somewhat greater than the external diameter of the pile, and provided at its upper end with inwardly projecting ears 22. When the shell is placed on the upper end of pile 9, ears 22 rest on the top of the pile and support the shell as in Fig. 2 with an annular space 24 between pile and shell. Conical 90 surfaces 21 act automatically to "center" the shell, i. e., force the shell to a position concentric with the pile and to hold it there during subsequent operations. In order to secure shell and pile together and prevent access of water to the pile pipe, space 24 is filled with grout, which, when set, binds shell and pile into an integral structure. In order 95 to hold the grout in place until set, it is necessary to temporarily close the lower end of

95

100

space 24. This is done by means of an annular plate 26, a top view of which is shown in Fig. 7. The plate is split on line 28, the adjacent surfaces being provided with wedge shaped ears 30 (Figs. 4 and 7) projecting outwardly and upwardly from the upper flat surface of the plate. The inner ends of ears 30 are so placed as to contact with the outer bottom of the shell 20 when it is in place. Lugs 32, similarly placed, serve to center the shell on the plate in the other direction. The circular opening in the center of plate 26 is of proper diameter to snugly fit around the pile pipe, whereby shell 20 is held concentric with the pile. Radial ribs 34, 36, and annular rib 38 underneath plate 26, serve to stiffen the plate. Each half of plate 26 is provided near each end with a hole 40, through which are secured wire cables 42, used for placing plate 26 around the pile beneath shell 20. This operation is performed under water by aid of the cables. Each cable connects adjacent ends of the two halves of plate 26. To place the plate in position, each cable is passed over a cross bar 44 supported by cable 46 which passes to a hoisting drum. One section of plate 26 is placed on each side of shell 20 and cable 46 is lowered until the plate sections are below the shell. The sections are then drawn up by cables 46, 42 against the bottom of the shell with ears 30 and 32 against the outer rim of the shell; and rib 38 against pile 9. Fig. 2 shows the parts in the position just described. Although plate 26 is now in proper position to close the bottom of space 24, it is not locked in place securely enough to resist displacement if grout be poured into space 24. The locking is performed by elongated loops 48, made preferably from round steel bars. The loops are hung one on each side of the shell, from blocks 50, supported on beam 52 laid across the top of shell 20, there being wedges 54 between beam 52 and blocks 50. The lower end of each loop 48 straddles a pair of ears 30 and is V-shaped, so that when wedges 54 are driven, the lower ends of the loops engage the sides of ears 30 to force them together and at the same time force them upwardly, thus holding the two halves of plate 26 firmly around the pile and firmly against the bottom of the shell, as in Figs. 3 and 4.

With plate 26 secured as above described, grout 56 is poured in any convenient manner, as for instance through spout 58 to fill space 24, as shown most clearly in Fig. 3. After the grout has set, wedges 54 are slackened off, loops 48 are taken off, and plate 26 is removed in two halves by means of cables 42, leaving the finished pile as in Fig. 8, with its upper end protected to a point below low water by the concrete shell integral with the pile proper.

The lengths of steel pipe are joined together by couplings 60 (Fig. 8). If one of

the couplings happens to be at the point where plate 26 is to be applied, a special plate is used with a central opening of proper diameter to engage the coupling.

It is to be understood that the invention is not limited to the specific embodiment herein illustrated and described but may be used in other ways without departure from its spirit as defined by the following claims.

I claim—

1. Apparatus for placing a shell around the upper portion of a pile in tide water, comprising in combination, a plate in sections, wedge-shaped ears on said sections, and means adapted for manipulation above water level for wedging said ears together to clamp said sections about said pipe below the shell after the lower end of the shell is submerged.

2. The invention set forth in claim 1, in which said wedging means comprises a steel loop having a lower end adapted to engage the surfaces of the wedge-shaped ears, substantially as described.

3. The invention set forth in claim 1, in which said wedging means comprises a steel loop having a lower end adapted to engage the surfaces of the wedge-shaped ears, and means for forcing said loops upwardly, substantially as described.

4. Apparatus for placing a shell around the upper portion of a pile in tide water, comprising in combination, means effective when the shell is placed on the pile for automatically forcing the upper end of the shell to a position concentric with the pile, and means adapted for manipulation above water level and effective below water level for forcing the lower end of the shell into concentricity with the pile.

5. The invention set forth in claim 4 in which said means effective below water level comprises a plate having centering ears mounted thereon.

6. Apparatus for placing a shell around the upper portion of a pile in tide water, comprising in combination, a plate in sections, ears on said sections, and means adapted for manipulation above water level for engaging said ears to clamp said sections about said pipe below the shell after the lower end of the shell is submerged, said ears serving also to center the shell relatively to the pile, substantially as described.

7. In the process of forming a concrete shell about a pile from a position above high water to a position below low water, the steps of placing about the pile a shell of sufficient inside diameter to provide an annular space between shell and pile, applying a plate about the pile below the shell after the lower end of the shell is submerged whereby the lower end of the annular space is sealed, and filling said space with grout.

8. In the process of forming a concrete

shell about a pile from a position above high water to a position below low water, the steps of placing about the pile a shell of sufficient inside diameter to provide an annular space between shell and pile, applying a sectional device about the pile below the shell after the lower end of the shell is submerged whereby the lower end of the annular space is sealed, filling said space with grout, and removing 10 said sectional device.

9. In the process of forming a concrete shell about a pile from a position above high water to a position below low water, the steps of placing about the pile a shell of sufficient 15 inside diameter to provide an annular space between shell and pile, manipulating devices above water level whereby a device is applied below water level for sealing the lower end of said annular space after the lower end of 20 the shell is submerged, and filling said space with grout.

10. In the process of forming a concrete shell about a pile from a position above high water to a position below low water, the 25 steps of placing about the pile a shell of sufficient inside diameter to provide an annular space between shell and pile, manipulating devices above water level whereby a device is applied below water level after the 30 lower end of the shell is submerged for sealing the lower end of said annular space, filling said space with grout, and removing said sealing device by manipulating said above-water devices.

35 11. The method of protecting a pile from erosion of tide water comprising the steps of placing about the upper end of the pile a concrete shell having internal ears thereon whereby the shell is suspended from the top 40 of the pile to provide an annular space between shell and pile to a point below low water level, sealing the lower end of said space after the lower end of the shell is submerged, filling said space with grout, and removing 45 the sealing device.

12. The invention set forth in claim 11 in which said sealing device is manipulated from above water level.

13. The method of protecting a pile from 50 erosion of tide water comprising the steps of placing about the upper end of the pile a concrete shell having internal ears thereon whereby the shell is suspended from the top 55 of the pile to provide an annular space between shell and pile to a point below low water level, applying a sectional sealing device about the pile below the shell after the lower end of the shell is submerged, and wedging 60 said device against the bottom of the shell.

In testimony whereof I hereto affix my signature.

JEREMIAH J. COLLINS.
